Primary Examiner — Vy Koenig(74) *Attorney, Agent, or Firm* — K. Lambert; Lambert Patent Services, LLC(57) **CLAIM**

The ornamental design for a step extender, as shown and described.

DESCRIPTION

FIG. 1 is a perspective view of the step extender, showing the new design;

FIG. 2 is a front perspective view thereof;

FIG. 3 is a top plan view thereof;

FIG. 4 is a bottom plan view thereof;

FIG. 5 is a first side elevational view thereof;

FIG. 6 is a second side elevational view thereof;

FIG. 7 is a front side elevational view thereof;

FIG. 8 is a rear side elevational view thereof;

FIG. 9 is a perspective view thereof, shown in a position of use with a ladder on a stairwell; and,

FIG. 10 is a perspective view thereof, shown in a position of use as a stepping stool.

The broken lines shown in the drawings depict environmental subject matter and form no part of the claimed design.
